D. F. LEPLEY,
OVERSPEED CONTROL FOR HOISTS,
APPLICATION FILED JAN. 22, 1921.

Patented June 13, 1922.

2 SHEETS—SHEET 2.

UNITED STATES PATENT OFFICE.

DANIEL F. LEPLEY, OF CONNELLSVILLE, PENNSYLVANIA.

OVERSPEED CONTROL FOR HOISTS.

1,419,154.

Specification of Letters Patent. Patented June 13, 1922.

Application filed January 22, 1921. Serial No. 439,206.

To all whom it may concern:

Be it known that I, DANIEL F. LEPLEY, a citizen of the United States, residing at Connellsville, in the county of Fayette and State of Pennsylvania, have invented a new and useful Overspeed Control for Hoists, of which the following is a specification.

This invention relates to an overspeed control for hoists, one of the objects of the invention being to provide a mechanism for use in connection with the drum of an inclined hoist such as shown, for example, in Patent No. 1,294,124, issued to me on Feb. 11, 1919, whereby the drum will not stop suddenly but will be kept under control up to, and make a gradual stop after the normal retardation period of the hoist has begun, the operation of this mechanism being automatic.

It is a well known fact that in all large slope or inclined hoists where long and heavy trips of cars are lowered, there is danger of excessive speed and costly wrecks where there is the slightest inattention on the part of the hoist operator. It is also a recognized fact that in vertical shaft hoists, where the drums are fast upon the shafts, excessive speed due to the lowering of heavy unbalanced loads often results in wrecking or seriously injuring the motor. These objectionable results have heretofore been overcome by making an emergency application of the brakes in order to bring the drums and motor to a sudden stop. In most cases this is as dangerous as the overspeed because it is likely to result in broken ropes or connections on cages or cars as well as injury to the armature windings of the motor.

An object of the present invention is to overcome the objectionable features by automatically maintaining the drum under control so that it can be gradually stopped as heretofore explained.

A still further object is to provide a brake mechanism by means of which there can be obtained a closer brake regulation with less manual effort than has heretofore been possible.

Another object is to provide a brake mechanism in which the maximum brake movement per unit of lever movement, is at the point of full application instead of at the point of full release.

With the foregoing and other objects in

view which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

In the accompanying drawings the preferred form of the invention has been shown.

In said drawings—

Figure 1 is an elevation of that portion of a hoist mechanism constituting the present invention certain cooperating parts being shown.

Figure 2 is a front elevation of a portion of an air brake engine forming a part of the mechanism and showing parts of the overspeed regulator in position thereon.

Figure 3 is a section through the casing of the air actuated plunger and showing, its connection.

Figure 4 is a section through the governor controlled valve forming a part of the mechanism.

Figure 5 is a plan view of the cam bar and cooperating parts.

Figure 6 is a side elevation showing a portion of the means for shifting the valves of the air engine.

Referring to the figures by characters of reference 1 designates a weighted arm fulcrumed as at 2 and connected by a rod 3 to the lever 4 which, as shown, is connected to the brake members 5 engaging the drum 6 of the hoist. The arm 1 is adapted to be actuated by air operated mechanism indicated generally at 7, the operation of this mechanism or engine being controlled by a governor 8 which receives its motion through suitable power transmitting mechanism 9 from the drum 6 and controls the actuation of a slide valve 10 shown in Figure 4. The casing 11 of this valve 10 has a pipe connection 12 leading direct to an air supply reservoir and is also provided with a vent 13 and an outlet pipe 14.

The parts thus far described do not constitute in themselves any part of the present invention but have already been disclosed in my patent hereinbefore mentioned and have been illustrated and referred to because they cooperate with the present invention to produce the results desired.

2

Mounted on the air brake engine 7 is a casing 15 provided with a bore 16 in which is slidably supported a plunger 17. The pipe 14 leads to the bottom of this bore so that when the drum is rotating at proper speed and the valve 10 is supported in normal position by the governor 8, there will be a pressure of air from the pipe 12 and through the casing 11 to the pipe 14 sufficient to hold the plunger 17 in raised position.

The plunger 17 is connected by a link 18 to a crank arm 19 extending from a shaft 20 journaled in the casing 15. One end of the shaft 20 is provided with a radial arm 21 normally extending horizontally and provided with an adjustable weight 22, this arm constituting means for moving the plunger 17 downwardly when relieved of the supporting action of the air thereunder. Another arm 23 extends downwardly from said end of the shaft and has an adjustable weight thereon as shown at 24, this arm acting as a pendulum and constituting a stabilizing medium.

Extending from the other end of the shaft 20 is a crank arm 25 having a link 26 extending downwardly therefrom forked and slotted longitudinally as shown at 27 and 30 which straddles the operating end of the floating lever 28 which operates the valve gear of the engine 7. It will be noted that the valve gear is connected to the arm 1 by a rod 29 attached to one of the arms of the valve gear lever 29'. See Figure 6.

Obviously in the event of total failure of air in the system the pendulum arm 23 will swing to a substantially vertical position and the plunger 17 will move downwardly within its casing 15. The arm 1 will drop of its own weight and the brakes will be applied as has been disclosed in mechanisms of this type heretofore patented by me and one of which has been illustrated in my patent hereinbefore mentioned. It might be stated that a pin 30 is carried by the lever 28 and projects into the slots 27 so that the link 26 and the lever 28 are thus constantly connected. After air pressure is restored in the system it will exert a lifting action upon the plunger 17 with the result that the pendulum arm 23 will be swung laterally and upwardly against a limiting stop 31 provided therefor and at the same time the weighted arm 21 and the link 26 will be elevated. Thus when the operating end of the counterweighted floating lever 28 of the engine valve mechanism is raised to the position it assumes when the brake is fully released, the pin 30 will assume a position within the top end of the slot 27. Obviously the pendulum arm will respond to the slightest reduction of air pressure under the plunger 17 and will swing downward toward a vertical position as the pressure is

reduced but will stop and remain stationary in any position at which the corresponding air pressure will balance it and will immediately assume its normal position upon the restoration of the normal air pressure. The movement thus imparted to the lever 28 and the corresponding actuation of the valves of the air engine 7 will result in a brake application or release as the case may require. Any degree of reduction in the air pressure under the plunger 17 will make a corresponding power brake application by forcing the operating end of the floating lever 28 downward (even against the power of the hoist operator) thereby to apply the brakes. As soon as the air pressure increases under the actuating plunger it will effect a corresponding release of the floating lever and permit the manual release of the brakes to that extent by the operator.

85
The lever employed for operating the valve mechanism of the air engine for the purpose of applying or releasing the brakes has been indicated at 32 and is secured to a shaft 33 constituting the fulcrum thereof and extending from this shaft and movable with the lever 32 are parallel arms 42 having a roller 43 journaled between the free ends thereof and working within a V-shaped cam slot 44 formed within a cam bar 45 which is 90 slidable between the arms 42. This bar has a longitudinal slot 46 through which the shaft 33 extends and one end of the bar is guided within a bracket 47 as shown. The other end of the bar is pivotally connected to 100 one arm of a bell crank 48 the other arm of which is attached to the operating end of the floating lever 28 by a link 49.

From the foregoing it will be noted that when the brake operating lever 32 is in its 105 central or intermediate position the roller 43 will be located in the center of the cam slot 44, the bar 45 being shifted to its left extremity, and the link 49 with its connected end of the floating lever 28 being in their 110 lowermost positions with the brake applied. By shifting the lever 32 in either direction from its center the cam bar 45 will be pushed toward the right by reason of the movement of the roller 43 within the cam slot 115 44 and, as a result, the link 49 will be actuated by the bell crank 48 so as to release the brake mechanism and permit it to be actuated by the automatic air controlled means heretofore described.

120
What is claimed is:—

1. In hoist mechanism the combination with a brake, a pressure operated engine, means operated by the engine for applying and releasing the brake, and a floating lever 125 for controlling the actuation of the engine, of a weight controlled plunger, means for directing pressure against the plunger to offset the action of its controlling weight, a governor controlled valve for regulating the 130

flow of pressure to the plunger, a hand operated lever for shifting the floating lever to actuate the engine and release the brake, and means operating automatically by the 5 failure of pressure against the plunger for automatically shifting the floating lever to apply the brake.

2. In hoist mechanism the combination with a brake, a pressure operated engine, 10 means operated by the engine for applying and releasing the brake, and a floating lever for controlling the actuation of the engine, of a weighted lever, a plunger movable therewith, means for directing pressure 15 against the plunger normally to overcome the action of the weighted lever, a governor controlled valve for regulating the pressure against the plunger, a hand operated brake controlling lever, means operated by the 20 movement of the lever in either direction from its central position for shifting the floating lever to actuate the valves of the engine to release the brake, and means operated by the actuation of the plunger when 25 relieved of its pressure for shifting the floating lever to brake applying position.

3. The combination with brake mechanism of a hoist and a pressure operated engine for actuating said mechanism, of a floating lever 30 for controlling the operation of the engine, a hand lever, and means operated by the movement of the hand lever in either direction from its central position for shifting the floating lever to release the brake, a plunger, 35 means for directing pressure against the plunger to hold it normally in one position, a weight for actuating the plunger when relieved of pressure, a governor controlled valve for regulating pressure against the 40 plunger, a link movable with the plunger, and a limited slidale connection between said link and the floating lever.

4. In a hoist the combination with a drum, a brake therefor and an engine for controlling the application of the brake, of a floating lever for controlling the actuation of the engine, a hand lever, means operated by the movement of the lever in either direction from its central position for shifting the 45 floating lever to release the brake, a plunger, means for directing pressure against the plunger normally to hold it in one position, a governor controlled valve driven by the drum for regulating pressure against the 50 plunger, gravity operated means for actuating the plunger when relieved of pressure thereagainst, and a member movable with the plunger and having a limited slidale connection with the floating lever.

5. In hoist mechanism the combination with a drum, a brake, an engine for actuating the same and a floating lever for controlling the actuation of the engine, of a hand lever,

arms extending from the fulcrum of the hand lever and movable therewith, a bar slidale 65 between the arms and having a cam slot, means carried by the arms and working within the cam slot for shifting the bar longitudinally in one direction during the movement of the hand lever in either direction from its central position, and means actuated by the bar for shifting the floating lever to control the actuation of the engine.

6. In a hoist the combination with a drum, a brake, an engine for actuating the brake 75 and a floating lever for controlling the actuation of the engine, of a hand lever, an arm movable therewith, a bar slidale relative to the arm, said bar having an angular cam slot, means carried by the arm and movable within the slot for shifting the bar longitudinally in one direction when the lever is moved in either direction from its central position, and means for transmitting motion from the bar to the actuating end of 80 the floating lever.

7. The combination with brake mechanism of a hoist and a pressure operated engine for actuating said mechanism, of a floating lever for controlling the operation of the engine, 90 a hand lever, and means operated by the movement of the hand lever for shifting the floating lever to release the brake, a plunger, means for directing pressure against the plunger to hold it normally in one position, 95 a weight for actuating the plunger when relieved of pressure, a governor controlled valve for regulating pressure against the plunger, and a relatively movable connecting means between the hand lever and the plunger for allowing actuation of the floating lever by the hand lever independently of the 100 plunger.

8. The combination with brake mechanism of a hoist and an engine for actuating said 105 mechanism, of means for controlling the operation of the engine, a lever, means operated by the movement of the lever for shifting the controlling means to release the brake, weighted means, means for directing pressure against the weighted means to hold it normally in one position, a governor controlled valve for regulating the pressure against said weighted means, and a connection between the lever and the weighted 110 means for allowing actuation of the controlling means by the lever independently of the weighted means.

In testimony that I claim the foregoing as my own, I have hereto affixed my signature in 115 the presence of two witnesses.

DANIEL F. LEPLEY.
